UNITED STATES PATENT OFFICE.

ELUE O. FRITCH, OF CUMBERLAND, MARYLAND, ASSIGNOR TO KELLY-SPRINGFIELD
TIRE COMPANY, OF CUMBERLAND, MARYLAND, A CORPORATION OF NEW JERSEY.

DESIGN FOR A VEHICLE TIRE.

Application filed February 13, 1928. Serial No. 25,435. Term of patent 14 years.

To all whom it may concern:

Be it known that I, ELUE O. FRITCH, a citizen of the United States, residing at Cumberland, in the county of Allegany and State of Maryland, have invented a new, original, and ornamental Design for a Vehicle Tire, of which the following is a specification, reference being had to the accompanying drawing, forming a part hereof.

The figure is a fragmental section of a portion of a tire showing a perspective of the design.

I claim:

The ornamental design for a vehicle tire as shown.

ELUE O. FRITCH.
